UNITED STATES PATENT OFFICE.

JAMES J. CURTIS, OF NEW YORK, N. Y.

QUOIN.

Application filed May 8, 1923. Serial No. 637,546.

To all whom it may concern:

Be it known that I, JAMES J. CURTIS, a citizen of the United States, and a resident of the city of New York, borough of Manhattan, in the county and State of New York, have invented a new and Improved Quoin, of which the following is a full, clear, and exact description.

This invention relates to quoins and particularly to an improved construction which will not become accidentally loosened even when appreciably jarred.

The object of the invention is to provide a strong construction which will not become loosened accidentally and which is formed so as to remain normally in a given position under the action of friction but which may be locked in any desired position at any time.

Another object of the invention is to provide a quoins in which the two parts thereof cannot become separated.

A still further object is to provide a quoins in which locks are provided at opposite ends designed to readily lock the quoins in any adjusted position at two points.

In the accompanying drawing—

Figure 1 is a side view of a pair of quoins disclosing an embodiment of the invention.

Figure 2 is a top plan view of the upper quoins shown in Figure 1.

Figure 3 is a sectional view through Figure 1 approximately on line 3—3, the same being on an enlarged scale.

Figure 4 is a side view of the locking member shown in Figure 3.

Figure 5 is a fragmentary sectional view through Figure 3, approximately on line 5—5.

Figure 6 is a fragmentary perspective view of a slightly modified form of locking means to that shown in Figure 3.

Figure 7 is a transverse sectional view through Figure 6, approximately on line 7—7.

Figure 8 is a fragmentary top plan view of the lower quoins shown in Figure 1.

Figure 9 is a sectional view through Figure 8, approximately on line 9—9.

Figure 10 is a transverse sectional view through Figure 8, on line 10—10.

Referring to the accompanying drawings by numeral, 1 and 2 indicate the two quoins which co-act to complete the pair of quoins as they are to be used. Heretofore, quoins having substantially the same general ap-

pearance have been provided but were merely loosely fitted together and would readily fall apart when not in use and under pressure. In addition, by reason of the fact that they loosely fit together and there is so much loose motion, the quoins do not always remain in position when under pressure.

In the present invention, the quoins 1 and 2 are so constructed as to normally remain in any given position by reason of their snug fitting ends. In addition, locking means are arranged at each end of each quoins to positively prevent any accidental sliding of either quoins. As shown in Figures 1, 2, 3, 4 and 5, the quoins 2 is provided with the usual teeth 3 for receiving a key used in adjusting the quoins and with a tongue 4 having its surface arranged at an angle to the bottom 5 of the quoins. The tongue 4 is not only provided with corrugations 6 on each side but is formed as a dovetail as shown in Figure 3 so that the opposite quoins may readily co-act therewith. The tongue 4' of the quoins 1 is also corrugated on the sides and is formed as a dovetail as illustrated particularly in Figure 3 whereby it may readily co-act with the underlying gripping portion or projection 7 and with the underlying or gripping portion 8 of the locking member 9.

From Figure 2, it will be observed that the large end of the quoins 2 is provided with a cut-out portion 10 in which the locking member 9 is placed, said locking member being chamfered at 11 so as to present a pivotal point 12 whereby when the set screw or locking screw 13 is tightened, the locking member 9 may be forced over tightly against the tongue 4'. Preferably, the projection 7 and also the underlying or gripping portion 8 is corrugated as shown in Figures 4 and 5 whereby they will more firmly grip the tongue 4' whenever in operation. In addition, the parts are made to rather snugly fit the tongue and, consequently, to resist accidental shifting movement. A pin 14 is mounted in the end of tongue 4' and acts to prevent the separation of the respective quoins 1 and 2. A locking structure similar to that illustrated in Figures 2 and 3 may be used in respect to the quoins 1 but preferably the structure shown in Figures 8, 9 and 10 is used. This construction consists of a solid locking block 15 slidingly mounted in the bore 16 of the quoins 1, said block being pro-

- vided with a groove 17 having underlying gripping portions 18 and 19 which may be smooth or corrugated as preferred and which act to grip the side walls of the tongue 4.
4. In order to cause a gripping action to take place, a rotatable actuating bar 20 is provided, said bar having flat surfaces 21 and 22 together with a central round portion 23, which round portion is smaller than the remaining part and thereby a groove is provided for accommodating the end of the screw 24. The ends of the actuating bar 20 are provided with a slot or kerf at each end for receiving a screw driver so that it may be rotated at any time but cannot be removed without first removing the screw 24. By turning the actuating bar 20 to the position shown in Figure 9 or turning the same until the rounded part of the bar engages the flat surface 25, the block 15 will be raised upwardly and, consequently, cause the members 18 and 19 to pinch the tongue 4. It will be noted that either of the locking members may be actuated at any time so as to lock the quoins in the position shown in Figure 1 or when they are moved to a different position.
- In Figures 6 and 7, a modified form of the invention is shown in which a single set screw 26 is used and acts to lock the parts together when properly adjusted. Two set screws of this kind may be used in respect to the two quoins or one set screw and one of the locking structures shown in Figures 3 and 4.
- What I claim is:
1. A quoin of the character described, comprising a body provided with a bead and arranged at an angle to the bottom of the body, said body being provided with a pair of upstanding members at one end forming a groove therebetween, said body at said upstanding members being provided with an opening, a clamping block arranged in said opening, said clamping block being formed with a pivotal point, and a set screw carried by one of said upstanding members for swinging said block on its pivotal point for causing the same to operate as a lock for locking a co-acting quoin in place. 45
2. A quoin, comprising a body, locking means carried by the body for locking a co-acting quoin thereto, said locking means comprising a swinging locking block, and a set screw for swinging said block into locking position. 50
3. A quoin of the character described, comprising a body and locking means carried by the body for engaging and locking a co-acting quoin, said locking means including a locking block formed with an underhanging portion adapted to engage the bead of the co-acting quoin, and a rotatable member for shifting the block to a position for causing said underhanging portion to move 65 to a gripping position. 60
4. A quoin, comprising a body provided with a bead and locking means for engaging and locking the bead of a co-acting quoin, said locking means comprising a movable block movable toward and from the side walls of said bead, and a threaded member traveling transversely of the bead and engaging the block for moving the same against said bead in order to lock the quoins 75 together. 70
5. A quoin, comprising a body provided with a bead and locking means for engaging and locking the bead to a co-acting quoin, said locking means comprising a locking block movable toward and from one of the side walls of said last mentioned bead, and means for moving said block toward said bead. 80

JAMES J. CURTIS.
